CLAIM

The ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the portion encircled in dot-dashed broken lines in FIG. 1;

FIG. 9 is an enlarged view of the portion encircled in dot-dashed broken lines in FIG. 2;

FIG. 10 is a cross-sectional view taken through line 10-10 of FIG. 9 in a fully opened state;

FIG. 11 is a cross-sectional view taken through line 10-10 of FIG. 9 in a partially folded state;

FIG. 12 is a cross-sectional view taken through line 10-10 of FIG. 9 in a fully folded state; and,

FIG. 13 is another front perspective view thereof in which the electronic device is shown in a fully folded state.

The broken lines in the figures depict portions of the electronic device which form no part of the claimed design. The dot-dash broken lines in the figures represent a boundary of the claimed design and form no part of the claimed design. The dot-dash broken lines in FIGS. 10-12 define the boundaries of the enlarged detailed showing of the cross-sectional views.
